[57] CLAIM

The ornamental design for a pipette, substantially as shown.

DESCRIPTION

FIG. 1 is a side elevational view of the pipette showing my new design, all side elevations being the same;
FIG. 2 is an end elevational view taken from the left side of FIG. 1;
FIG. 3 is an end elevational view taken from the right side of FIG. 1; and
FIG. 4 is a side elevational view of a modification thereof.
